E. MAWDSLEY.

SASH LIFT AND LOCK.

APPLICATION FILED MAR. 7, 1910.

970,526.

Patented Sept. 20, 1910.

UNITED STATES PATENT OFFICE.

ELIZA MAWDSLEY, OF ALTON, ILLINOIS.

SASH LIFT AND LOCK.

970,526.

Specification of Letters Patent. Patented Sept. 20, 1910.

Application filed March 7, 1910. Serial No. 547,907.

To all whom it may concern:

Be it known that I, ELIZA MAWDSLEY, citizen of the United States, residing at Alton, in the county of Madison and State 5 of Illinois, have invented certain new and useful Improvements in Sash Lifts and Locks, of which the following is a full, clear, and exact description, reference being had to the accompanying drawings, forming a 10 part hereof.

My invention has relation to improvements in sash-lifts and locks; and it consists in the novel details of construction more fully set forth in the specification and 15 pointed out in the claim.

In the drawings, Figure 1 is a front elevation of my sash-lift and lock, with sashes and window frame shown dotted; Fig. 2 is a horizontal section on the line 2—2 of Fig. 20 1; Fig. 3 is a vertical sectional detail on the line 3—3 of Fig. 5; Fig. 4 is an enlarged horizontal sectional detail on the line 4—4 of Fig. 1, with sash shown in full; Fig. 5 is a vertical enlarged sectional detail on the 25 line 5—5 of Fig. 2; and Figs. 6 and 7 represent diagrammatic views showing the course of travel of the cables for lifting the lower sash or raising the upper sash (when the latter has been lowered).

30 The object of my invention is to construct a combined sash-lift and lock, by which either the lower or upper sash may be manipulated and controlled through the operation of a common actuating spindle or shaft, either sash being opened or closed as desired, and when opened to any distance, may be automatically locked, so that a window can be left open to any desired degree without danger of the sash changing its 35 position.

The advantages of the invention will be better apparent from a detailed description thereof which is as follows:—

40 Referring to the drawings, F represents the window-frame, S the lower and S' the upper sash as usual.

D represents the sill, and B a box or casing below the sill in the wall of the house, wherein a portion of the operating parts of 45 the device are housed, another portion being exposed on the outside of said casing. Mounted between the front and rear vertical walls of the casing is a spindle or shaft 1, the inner end of which terminates in a 50 head 2 operating in a cavity 3 in the rear

wall, the head preventing the accidental withdrawal of the spindle, and the cavity allowing for the necessary longitudinal movement to which the spindle is subjected as presently to be seen. Mounted loosely on 60 the spindle are a pair of sprocket wheels 4, 4', identified respectively with the sashes S, S'. The sprocket wheels are spaced apart by their abutting hub portions h, h' in which are formed the contiguously located 65 grooves 5, 5' respectively, said grooves being adapted to alternately receive or be brought into coöperation with, the feather 6 carried by the spindle, the spindle being movable longitudinally in its bearings a sufficient distance to bring the feather 6 into engagement with the groove 5 of the sprocket 4, and then with the groove 5' of the sprocket 4', depending on which sash is to be raised or lowered. In this longitudinal movement or shifting, the spindle is limited in one direction or outwardly by the head 2, and inwardly by the ratchet disk 7 mounted on the outer projecting portion 70 of the spindle, the ratchet arresting such 75 inward movement by coming in contact with the outer wall of the casing B. The outer end of the spindle terminates in a hand-wheel 8 provided with a handle 9. The ratchet disk is engaged by a pawl 10 substantially of the form as shown (Fig. 3), the 80 pawl being normally held in engagement with the ratchet by a flexed spring 11, the parts being mounted on a suitable plate 12. The sprocket-wheels 4, 4' are peripherally 85 grooved, the teeth being disposed on each side of the groove, so that each sprocket has two sets of teeth, each set engaging its own sprocket chain, one chain a having its inner 90 vertical lap secured by staples 13 to one side 95 of the sash S, and the other chain b having its inner vertical lap correspondingly secured to the opposite side of the same sash a like arrangement applying to the sash S'. The chain a passes around suitable guide 100 pinions or idlers m, the chain b passing around corresponding idlers m', and an additional idler n, all disposed on the window frame. The two horizontal bottom laps of the chain a pass around the outer set of teeth 105 of the sprocket wheel 4, (Fig. 2,) the upper horizontal lap of the chain b engaging the bottom of the inner set of teeth of the wheel 4, while the lower horizontal lap passes loosely over the smooth periphery of the 110

wheel between the teeth. What is true of the chains operating one sash S , is true of the chains operating the sash S' , and a description of one will answer for the other.

- 5 If we turn the hand-wheel 8 to the left as indicated by the arrow (Fig. 1) the draft on the two chains will be in a direction to exert a pull on the outer vertical laps of both chains, a, b , so that the sash S will be raised; and if released will be locked by the locking pawl 10 which prevents the ratchet 7 mounted on the spindle 1 from rotating in the opposite direction. To lower the sash S , the operator disengages the pawl 10 from the ratchet, turning the wheel 8 and spindle 1 in the opposite direction, which has the effect of pulling down on the sash, the latter being assisted by gravity in its descent. In order to operate the ratchet 4, the spindle 1 is pulled out so as to draw the feather 6 into the groove 5 of the hub h . By pushing the shaft 1 inwardly its full limit, the feather 6 will be withdrawn from engagement with the ratchet 4, entering the groove 5' of the ratchet 4', (Fig. 5), whereby the upper sash S' may now be lowered. Since to lower or open the upper sash, it must be moved downward, the operator releases the pawl 10 from the ratchet, turning the spindle 1 to the right (or opposite to what would be the direction for raising the lower sash) which draws the upper sash down. By releasing the pawl, the sash is locked against an upward movement until restored by the operator by a turn of the spindle to the left. The dimensions of the pawl and ratchet are relatively such as to permit of a permanent engagement between them for either of the extreme positions of the spindle, it being understood that the longitudinal movements of the spindle to effect engagement with either of the sprockets 4, 4' is insufficient to disengage the pawl from its ratchet. When the spindle is shoved in half-way so as to cause the feather 6 to simultaneously engage the grooves 5, 5' of both wheels 4, 4', it is apparent that an unauthorized person can not move either sash from the outside of the window, as the wheels would be locked

by the feather 6 against movement in either 50 direction.

In Figs. 5 and 6, I illustrate diagrammatically the separate chains or cables so that the direction of travel thereof for a raising of the lower sash (or a closing movement of 55 the upper sash if previously lowered) is obvious at a glance from an inspection of the arrows. Of course, a reverse travel of the chains would correspond to a closing movement of the lower sash or a lowering of 60 the upper sash as obvious.

The spindle 1 is prevented from being accidentally withdrawn by the inner limiting head 2 which strikes the wall at the side of the cavity 3.

Having described my invention, what I claim is:

In combination with a vertically movable upper and lower sash, endless sprocket chains secured to the sides of the respective 70 sashes, idler pulleys for the chains, a centrally disposed rotatable longitudinally movable spindle mounted at the base of the window frame, a pair of loosely mounted peripherally grooved sprocket wheels with 75 teeth on each side of the groove carried on the spindle, means on the spindle and sprocket wheels for effecting alternate engagement between the respective wheels and spindle according to the direction of longitudinal movement imparted to the spindle, a ratchet on the spindle, a locking pawl therefor, one chain on the one side of each sash having a pair of laps meshing with the teeth on one side of the peripheral groove 85 of its corresponding sprocket wheel, the other chains having each one lap meshing with the teeth on the opposite side of the groove, and another lap passing loosely along the groove, the parts operating substantially as and for the purpose set forth.

In testimony whereof I affix my signature, in presence of two witnesses.

ELIZA MAWDSLEY.
